Primary Examiner — Thomas Johannes
Assistant Examiner — Shawn T Gingrich

(57) **CLAIM**

The ornamental design for a multi-use bag tie, as shown and described.

DESCRIPTION

FIG. 1 is a perspective view of a multi-use bag tie showing my new design;

FIG. 2 is a top plan view thereof;

FIG. 3 is a perspective view thereof, shown in an alternate position of use;

FIG. 4 is top view thereof, shown in an alternate position of use;

FIG. 5 is a perspective view thereof, shown in second alternate position of use;

FIG. 6 is a top plan view thereof, shown in second alternate position of use;

FIG. 7 is a front elevation view thereof, in an environment of use; and,

FIG. 8 is a front view thereof, in a second environment of use. The broken line portion of the figure drawings is included to show environment that forms no part of the claimed design.

1 Claim, 4 Drawing Sheets
